UNITED STATES PATENT OFFICE

HAROLD E. HALLENBECK, OF HUDSON, NEW YORK, ASSIGNOR TO GIFFORD-WOOD COMPANY, OF HUDSON, NEW YORK, A CORPORATION OF NEW YORK

SELF-REVERSING TROLLEY BUCKET

Application filed November 11, 1929. Serial No. 406,470.

This invention relates to trolley bucket installations, for handling coal, sand, gravel and the like; and among other objects, it aims to provide a bucket of this character with a limit switch or limit switches, so constructed and arranged that descent of the bucket is automatically stopped as the material being piled is reached, the bucket then discharging and automatically starting up again.

10 In the accompanying drawings,—

Fig. 1 is a diagrammatic view of a trolley bucket with a limit switch mounted thereon, in accordance with the invention;

15 Fig. 2 is a wiring diagram; and

Fig. 3 is a perspective of a typical trolley bucket installation, omitting the pit or pocket into which the bucket descends.

In accordance with the invention, a bucket 5, preferably of substantially the same construction as the one claimed in Patent No. 1,741,123, dated December 24, 1929, has trip pads 6 for tripping the latches which hold the bottom leaves in closed position. These trip pads are so constructed and arranged 20 that they will come in contact with the coal or other material being handled before the bucket proper reaches the pile, thus opening the bucket just as the top of the pile is encountered.

30 Heretofore, it has been necessary for the operator (who is almost invariably unable to see the material as it discharges from the bucket) to reverse the hoist motor when he thinks the material is discharged, thus elevating the bucket. There is much time lost, in the course of a day's work, while an operator brings a bucket to a stop, waits a moment for the discharge, and starts it up again. Operators are usually not particularly impressed by the value of eliminating a few seconds' delay in effecting each operation, and frequently are deliberately dilatory. Hence, 35 automatic return of the bucket is a most desirable feature of a trolley bucket installation.

The preferred form of the invention has a limit switch 7 mounted on the bucket and connected by wires running through a cable 8 to the circuit which controls the hoist motor. As shown, the limit switch is set to permit

lowering of the bucket except as it is released by the trip pad upon contact of the latter with the pile. When so moved, a circuit is completed which reverses the motor, initiating hoisting. Cable 8 may be a very light weight rope, so as to have no tendency to tilt the bucket and spill its contents.

The reversing of limit switch 7 is biased by a compression spring 9 to open the lowering circuit, and is released (by contact with the pile of a member carried by the bucket) to close the hoisting circuit, as Fig. 2 shows. Preferably, as shown, the trip pads 6 are used to release the limit switch; but obviously a separately pivoted or slideable member (not shown) projecting downwardly from some part of the bucket may be used to release the limit switch. As the pile rises, necessarily the descent of the bucket becomes less: hence a motor driven limit switch cannot be used.

In order to make it practicable to mount a motor-governing switch on the bucket, the cable 8 is carried on a drum 10 which is a retrieving drum, that is, it winds up the cable as fast as the bucket ascends, thus preventing fouling of the cable with a bin or with the runway structure, as will be understood by referring to Fig. 1 of the W. H. Towne application Ser. No. 146,890, owned by the assignee of this application. The drum 10 is carried on the trolley from which the bucket is hung by a 2-fall hoist line, as will be understood from said Towne application. The retrieving action may be obtained by a counterweight 11 and cable 12 wound 40

reversely about the shaft of drum 10 or about another drum 13, as shown. Instead of a counterweight, springs may be used, as when the counterweight would be impracticable on account of interference with the bin walls. The wires 14, which are carried by the cable 8, are led to insulated conductors (not shown) inside drum 10, which conductors are connected to insulated slip rings 15 with which

brushes 16 contact, wires 14 connecting with the motor control circuit and push button circuits, as Fig. 2 indicates. The motor used is for three phase alternating current, and may be either of the slip ring or squirrel cage type, preferably the former.

In the operation of the bucket, during descent the lowering contactor, shown in Fig. 2, will be closed and its auxiliary contact will be open. The circuit holding the lowering contactor closed includes wires 14, 14^a and the closed limit switch 7. When tripper 6 comes in contact with the pile of material it is forced upwardly so as to cause compression spring 9 to force open the limit switch contacts, which breaks the circuit through wires 14, 14^a, thus causing the lowering contactor to open, stopping the down motion of the bucket. When this happens, the auxiliary contact closes, thus completing the circuit through wires 20, 20^a to the hoisting contactor coil, thus closing the hoisting contactor by electro-magnetism. This initiates the upward motion of the bucket.

As the motor is provided with a solenoid 20 brake (Fig. 2), as soon as the current is cut off, the motor is stopped, and in the meantime the connections have been reversed as described, releasing the solenoid brake and starting the bucket up again. The reversal 25 of the motor takes place almost immediately, without injury to the motor, and without even a time relay being used, as Fig. 2 shows. The bucket starts dumping before it actually reaches the pile and completes its dumping as it starts to rise, which is advantageous 30 when handling coal, as breakage is thereby reduced to a minimum.

Obviously the present invention is not restricted to the particular embodiment there- 35 of herein shown and described.

What is claimed is:—

1. An electrical trolley bucket installation comprising, in combination, a dumping bucket; a trip pad on the bottom of the 40 bucket; a latch normally holding the bucket closed and disengaged upon upward movement of the trip pad, as when the trip pad comes in contact with the pile of material; a limit switch on the bucket and arranged to be 45 operated by the trip pad; a reversible motor for hoisting and lowering the bucket; and electrical circuits controlled by said limit switch, said circuits having reversing contactors and control switches for effecting low- 50 ering of the bucket until the limit switch is moved, then automatic stopping of the bucket, and then immediate hoisting automatically.

2. An electrical trolley bucket installation 55 comprising, in combination, a dumping bucket; a limit switch on the bucket; a reversible motor for hoisting and lowering the bucket; switch operating means on the bucket arranged to move the switch as the bucket 60 comes in contact with the pile of material; and electrical connections for effecting automatic stoppage and reversal of the motor upon such movement of the switch.

3. An electrical trolley bucket installation 65 comprising, in combination, a dumping

bucket; a limit switch on the bucket; switch operating means on the bucket arranged to move the switch as the bucket comes in contact with the pile of material; a reversible motor for hoisting and lowering the bucket; electrical connections for effecting automatic stoppage and reversal of the motor upon such movement of the switch; said electrical connections comprising wires leading to the limit switch and means electrically connected to said wires for reversing the motor; a cable sheathing the wires; and a retrieving drum for automatically winding up and paying out the cable as the bucket rises and descends. 70

4. An electrical trolley bucket installation 75 comprising, in combination, a trolley movable back and forth along a track; a bucket suspended from the trolley by a hoist line and traveling therewith; an electric motor for said hoist line; a drum rotatably mounted 80 on the trolley; a limit switch on the bucket; means on the bucket to move the limit switch when the underside of the bucket comes in contact with a pile of material; conductors connected to the limit switch and extending up to the drum; means to effect automatically 85 winding up of the conductors on the drum; and means electrically connected through the drum with said conductors to cause automatic reversal of the bucket whenever, during low- 90 ering, its limit switch is moved by contact of the bucket with the material. 95

5. An electrical trolley bucket installation 100 comprising, in combination, a trolley movable back and forth along a track; a bucket suspended from the trolley by a hoist line and traveling therewith; an electric motor for 105 said hoist line; a limit switch on the bucket; means on the bucket to move the limit switch when the underside of the bucket comes in contact with a pile of material; conductors connected to the limit switch; said conductors being electrically connected with slip rings on the drum shaft; brushes in contact 110 with the slip rings; wires connected to said brushes; and a motor control circuit comprising a hoisting contactor, a lowering contactor, a control switch for effecting hoisting, a control switch for effecting lowering, and an auxiliary contact on the lowering contactor for effecting automatic reversal of the motor when the bucket is lowered into contact with the pile of material. 115

6. An electrical trolley bucket installation 120 comprising, in combination, a trolley movable back and forth along a track; a bucket suspended from the trolley by a hoist line and traveling therewith; an electric motor for moving said hoist line; a drum rotatably mounted on the trolley; a limit switch on the bucket; means on the bucket to move the limit switch when the underside of the bucket comes in contact with a pile of material; conductors connected to the limit switch and extending up to the drum; means to effect 125

automatically winding up of the conductors on the drum; said conductors being electrically connected with slip rings on the drum shaft; brushes in contact with the slip rings; 5 wires connected to said brushes; and a motor control circuit comprising a hoisting contactor, a lowering contactor, a control switch for effecting hoisting, a control switch for effecting lowering, and an auxiliary contact 10 on the lowering contactor for effecting automatic reversal of the motor when the bucket is lowered into contact with the pile of material.

In testimony that I claim the foregoing as my own, I have hereto affixed my signature.
